LUMINOUS PRICE SIGN

Lawrence F. Brown, Oakwood, Ohio

Application August 14, 1933, Serial No. 684,969

4 Claims. (Cl. 40—131)

This invention relates to new and useful improvements in luminous price signs.

It is one of the principal objects of my invention to provide a simple and efficient luminous price sign having clear legibility in the daytime and at night, for attachment to gasoline pumps, light globes and other objects.

Another object of my invention is to provide a price sign which is illuminated cost free from a globe sign, for visibility at a great distance day and night. The light from the globe will shine through the sign, which may be backed with white coated, red glass, giving a white number with a black background in the daytime, and an illuminated red number at night.

All character plates in the sign are interchangeable, and tax and cash discount characters may be added to them if desired.

Other important and incidental objects will be brought out in the following specification, and particularly set forth in the subjoined claims.

In the accompanying drawing, Figure 1 is a front view of a gasoline pump to which my price sign is secured. Figure 2 is an enlarged front view of the price sign. Figure 3 is a cross sectional view taken through the sign on the line 3—3 of Figure 2. And Figure 4 is a longitudinal sectional view taken through one of the offset character plates.

Referring to the accompanying drawing for a detailed description of the various forms of embodiment of my invention, the numeral 1 in Figures 1, 2 and 3 designates a gasoline pump casing to which a dial cover plate 2 is secured by a bezel ring 3. Attached to the bezel ring 3 by screws 4 is a bracket plate 5 formed with a central hole 6 to receive the socket 7 of an electric light bulb 8, that is secured in the casing 1.

Integral with the lower edge of the plate 5 are legs 9, 9 that receive the screws 4, 4 and brazed, soldered or otherwise suitably secured to the opposite sides of the bracket plate 5, are two outwardly inclined U-shaped channel frames 10 and 11 which are secured at their outer ends by soldering or other suitable means to a narrow, central channel frame 12 parallel with the bracket plate 5 to receive a removable opaque price plate 13 and a transparent background member 14. The price plate 13 may be punched as illustrated in Figure 2 to designate the cost of a number of gallons from one to 15, at the price per gallon appearing on the character plates 16 insertable in the channel frames 10 and 11.

Each character plate 16 formed with a die cut opening shaped to represent a certain character,

is inserted in its respective channel frame in front of a transparent background member 17. The plates 16 are offset at one side edge so that these edges may have an overlapping fit between the characters.

On each side of the price plate 13, the plates 16 in Figure 2 contain die-cut slots that represent the price per gallon, in this instance 17 cents. This price may be easily changed to conform with the prevailing rate per gallon by changing one, or both plates 16, on either side of the sign, and inserting a new total price plate 13 in the center channel frame 12.

When the proper price plates are inserted in the channel frames 10, 13 and 11, the rays emitted by the bulb 8 will shine through the transparent background members 17, 17 and the price plates in front of them, to produce a sharp, clear, luminous sign that may be read easily from the front and the side at a distance. The background members 17, 17 may be white-coated red glass to give a white number with a black background in the daytime, and an illuminated red number at night. As shown at Figure 2, the plates 13 and 16 are formed with integral top marginal beads or flanges to effectively close the top open ends of their respective channel frames 10, 11 and 12. By these beads or flanges the plates 13 and 16 may be easily removed when price changes are made.

Having described my invention, I claim:

1. A luminous sign for an illuminated fuel dispensing pump comprising a support, an auxiliary source of light carried by said support, a pair of outwardly inclined channel frames secured to said support, a channel frame secured to the outer ends of the inclined channel frames in parallelism with the support and in front of said light source, transparent members insertable in the channel frames, interchangeable price per unit plates formed with character shaped openings, insertable in the inclined channel frames in front of the transparent members, and a total price plate insertable in the middle channel frame in front of the transparent member 100 therein.

2. A luminous sign for gasoline pumps, comprising a pump casing, a dial, a bezel ring for said dial, a bracket member secured to said bezel ring, an electric lamp bulb secured to said casing and above said dial, a pair of outwardly inclined channel frames secured to said bracket member, a channel frame secured to the outer ends of the inclined channel frames, in parallelism with said bracket member and in front 110

of said bulb, transparent members insertable in the channel frames, interchangeable price per gallon plates formed with character shaped openings, insertable in the inclined channel frames
 5 in front of the transparent members therein and in the path of the rays from said bulb, and a plate displaying total prices at the price per gallon shown by the inclined plates, insertable in the middle channel frame in front of the
 10 transparent member therein.
 3. A luminous sign for an illuminated fuel dispensing pump comprising a support, an auxiliary light source carried by said support, a channel frame encompassing said auxiliary light
 15 source and attached to said support, transparent members insertable in said channel frame in front of said auxiliary light source and interchangeable price plates formed with character shaped openings insertable in said channel frame in front
 20 of said transparent members.

4. A luminous sign in combination with a dial light for a fuel dispensing pump, comprising a support, a meter dial carried by said support, a light source above said dial, a pair of outwardly inclined channel frames secured to said support, a channel frame secured to the outer ends of the inclined channel frames in parallelism with the support and in front of and encompassing said light source; transparent members insertable in the channel frames, interchangeable price per unit plates formed with character shaped openings, insertable in the inclined channel frames in front of the transparent members, and a total price plate insertable in the middle channel frame in front of the transparent member therein. 80
